(57) CLAIM

The ornamental design for a nasal aspirator set with interchangeable tips, as shown and described.

DESCRIPTION

FIG. 1 is a perspective view showing an assembled state with a first tip of a nasal aspirator set with interchangeable tips;

FIG. 2 is a perspective view showing an assembled state with a second tip of the nasal aspirator set with interchangeable tips;

FIG. 3 is a perspective view showing an assembled state with a third tip of the nasal aspirator set with interchangeable tips;

FIG. 4 is a perspective view showing a detached state with the first,second and third tip of the nasal aspirator set with interchangeable tips;

FIG. 5 is a front view showing a detached state with the first, second and third tip of the nasal aspirator set with interchangeable tips;

FIG. 6 is a rear view showing a detached state with the first,second and third tip of the nasal aspirator set with interchangeable tips;

FIG. 7 is a left side view showing a detached state with the first,second and third tip of the nasal aspirator set with interchangeable tips;

FIG. 8 is a right side view showing a detached state with the first,second and third tip of the nasal aspirator set with interchangeable tips;

FIG. 9 is a top plan view of the entire assembly including four components of the present invention in a detached status; and,

FIG. 10 is a bottom plan view of the entire assembly including four components of the present invention in a detached status.

The broken line shown in FIGS. 6 and 10 illustrate portions of the nasal aspirator set with interchangeable tips that form no part of the claimed design.

1 Claim, 10 Drawing Sheets
